US00D823866S

(12) **United States Design Patent** (10) Patent No.: **US D823,866 S**
(45) Date of Patent: **** Jul. 24, 2018**

(54) **DISPLAY SCREEN WITH GRAPHICAL USER INTERFACE**

(71) Applicant: **Under Armour, Inc.**, Baltimore, MD (US)

(72) Inventors: **Scott Laing**, Baltimore, MD (US); **Brian Carden**, Baltimore, MD (US); **Daniel Townson**, Baltimore, MD (US); **Eric Boam**, Baltimore, MD (US); **Marcus Piña**, Baltimore, MD (US); **Kate Dubuisson**, Baltimore, MD (US); **Andrew Moore**, Baltimore, MD (US)

(73) Assignee: **Under Armour, Inc.**, Baltimore, MD (US)

(**) Term: **15 Years**

(21) Appl. No.: **29/631,121**

(22) Filed: **Dec. 27, 2017**

Related U.S. Application Data

(62) Division of application No. 29/539,267, filed on Sep. 11, 2015.

(51) LOC (11) Cl. **14-04**

(52) U.S. Cl.

USPC **D14/485**

(58) **Field of Classification Search**

USPC D14/485-495

CPC G06F 3/0482; G06F 3/04817

CLAIM

The ornamental design for a display screen with graphical user interface, as shown and described.

DESCRIPTION

The FIGURE is a front view of a display screen with graphical user interface showing our new design. The broken lines shown in the drawings illustrate portions of the display screen with graphical user interface that form no part of the claimed design.
